CLAIM

The ornamental design for a display unit for injection device, as shown and described.

DESCRIPTION

FIG. 1 is a left perspective view of a display unit for injection device showing my new design;

FIG. 2 is a right perspective view thereof;

FIG. 3 is a front perspective view thereof;

FIG. 4 is a front view thereof;

FIG. 5 is a rear view thereof;

FIG. 6 is a right side view thereof; and,

FIG. 7 is a left side view thereof.

The broken line showing of parts of the drawings is included for the purpose of illustrating use and environment and forms no part of the claimed design.
